DEVICE FOR PREDETERMINING FITTING LENGTHS OF ORNAMENT STRINGS

Philip Tell, Madison, and Abraham Lehrhoff,
Morristown, N. J.

Application June 25, 1947, Serial No. 756,856

10 Claims. (Cl. 33—179)

1

This invention relates to a device for predetermining a length or lengths of strung beads, pearls and other gems, or other forms of strung ornaments which may be required to size necklaces, bracelets or the like, composed thereof, to fit the person of an individual wearer.

In making up necklaces, bracelets and similar articles of adornment which comprise a multiplicity of beads, pearls, gems or other ornamental elements strung in succession upon a carrying strand, it is desirable to predetermine the number of such elements, required with respect to a given string thereof, which will provide a proper string length calculated to accommodate itself to or fit the person of the individual by whom it is to be worn; this is especially desirable with respect to necklaces comprising a plurality of strings, as, for example, necklaces of the so-called "choker" type, which consist of a plurality of substantially parallel strings, the respective lengths of which must be relatively varied in order to assure proper lie thereof about and upon the neck of the wearer.

Having the circumstances above set forth in view, it is an object of this invention to provide a simple and effective measuring device, which can be easily and quickly manipulated, whereby to predetermine the number of elements necessary to produce a string or strings thereof of required length or of required relative lengths calculated to size the article, comprising such string or strings, to properly fit the person of a given individual wearer.

Other objects of this invention, not at this time more particularly enumerated, will be understood from the following detailed description of the same.

Illustrative embodiments of the measuring device of this invention are shown in the accompanying drawings, in which:

Figs. 1 and 2 are respectively pictorial views showing application of the measuring device of this invention to the neck of a person to be fitted with a strung ornament article of adornment.

Fig. 3 is a front face view of the measuring device; Fig. 4 is a fragmentary rear face view thereof; Fig. 5 is a fragmentary side elevational view thereof; Fig. 6 is an end elevational view of the part shown in Fig. 5; Fig. 7 is a fragmentary perspective view of the device; and Fig. 8 is a fragmentary view showing the measuring device as applied to the neck of an individual for whom the measurement is being made.

Figs. 9 and 10 are respectively enlarged views of forms of tensioning means adapted for use on

the free terminals of the measuring strings of the device.

Fig. 11 is a fragmentary face view of disconnected meeting end portions of the measuring device as equipped with separable clasp means for joining said ends; and Fig. 12 is a similar view showing the clasp means connected to join the meeting ends of the device.

Similar characters of reference are employed 10 in the above described views, to indicate corresponding parts.

To illustrate the construction and mode of use of the measuring device embodying this invention, the same has been shown as employed for predetermining the number of beads required to provide relative string lengths thereof to be arranged to form a pearl necklace of the so-called "choker" type comprising three strings. As 15 specifically designed for this and similar uses, 20 the measuring device comprises bead or like elements 11 of a size corresponding to the size of the pearl beads to be used in the make up of the necklace, said beads 11 being strung successively upon carrying strands 12 so as to form a plurality 25 of strings thereof; in the illustrative case, three such strings A, B and C being provided, each comprising a predetermined number of beads 11.

Said strings A, B and C are each secured, by 30 one end of the strand 12 thereof, to a measuring coupler element, so that said strings extend from the latter in parallel relation. The measuring coupler element, in a simple form thereof, comprises a flat plate-like body 13, having, spaced 35 along its inner transverse marginal portion, a series of perforations or eyes 14 engageable by means for securing the strands 12 of the respective strings to said body 13. The fastening connection of the strands 12 to the eyes 14 may be 40 made in any suitable manner, as e. g. by knotting the ends of the strands after passing said ends through said eyes 14, but preferably the fastening connection is made by means of connecting links or stirrups 15 which are engaged through the eyes 14, and by which knotted strand ends are embraced (see Fig. 5). The plate-like body 13 may be made of any suitable material, but is preferably made of sheet metal. The outer transverse part of the body 13 is curved 45 outwardly and inwardly to provide a coupler portion 16 adapted to form, along its inner or rearward face, a rearwardly open bead seating channel 17. The free marginal part of said coupler portion 16 is indented by entering slots, respectively indicated by the reference characters a,

b and *c*. Said slots are spaced apart correspondingly to the spacing of the bead strings A, B, and C which are anchored to and extend from the rearward transverse marginal portion of the body 13, being disposed in longitudinal alignment with said strings. Said slots *a*, *b* and *c* are of length adapted to intersect the medial line of the bead seating channel 17, and are of width slightly exceeding the thickness of the strands 12 of the bead strings, so as to readily permit entrance and passage of said strands thereinto.

Each bead string A, B and C comprises a selected number of beads 11 depending upon the diametric size thereof; a selected plurality of said beads adjacent the free end portion of each string being identified by numbers corresponding to their numerical positions in the whole number of beads by which the string is constituted. For example, if each string comprises fifty-two beads, the last eighteen thereof are successively numbered from 35 to 52 inclusive (see Figs. 3 and 8). This is on the assumption that in a finished necklace, comprising a plurality of parallel strings, none of said strings would be required to be shorter than a length formed by thirty-four beads or pearls. It will be understood that the number of beads in the strings A, B and C may be varied, and also that the number of numerically identified beads at the free terminal end portions of the strings is also subject to variation, as may be required by the diametric size of beads or pearls to be used in the make up of a necklace, bracelet or similar article, or as may be required by the specific form or type of necklace, bracelet or the like with reference to which measurements are desired to be made. Furthermore, if desired, all of the beads of the strings forming the measuring device may be successively numbered from fixed ends to free ends of said strings.

It is desirable that the beads 11 of the respective measuring strings, be kept in substantial abutment one upon another, so as to assure uniform spacing thereof throughout the string length, without intervening gaps. Ordinarily, if the free end of a strand 12 is knotted and the formed knot caused to closely or tightly abut the terminal bead so as to crowd the succession of beads into desired abutment one upon another, this would be sufficient. However, stretching or expansion and contraction of the strand 12 might well disturb the desired abutting relationship of the beads, so as to permit undesirable gaps to form in the strings thereof. To avoid this possibility, means may optionally be provided for either automatically or manually adjusting the beads to assure the desired abutting relationship thereof. One such means, as shown in Fig. 9, provides an automatically acting means for accomplishing the purpose, said means comprising a compression spring 18, the inner end of which abuts the outermost or terminal bead 11 of a string thereof, and the outer end of which is footed in a perforate seating washer 19 through which the strand 12 extends and terminates in a knotted portion 20 by which said seating washer is supported. Another means which is manipulatable to assure desired abutting relationship of the beads, as shown more particularly in Fig. 10, is provided by a longitudinally extensible thrust exerting device comprising an internally screw-threaded barrel 21 having a perforate end wall to abut the outermost or terminal bead 11 of a string thereof and through which

the strand 12 of the string is passed, and an externally screw-threaded thrust member 22 which is screwed into said barrel 21. Said thrust member 22 is also provided with a perforate end wall through which the strand 12 extends and terminates in a knotted portion 23 by which said thrust member 22 is supported. It will be obvious that by relatively turning the thrust member 22 and barrel 21, these parts may be extended so as to exert thrust upon the beads effective to move the same along the strand 12 into the desired abutting relationship.

In the use of the measuring device, as e. g. for determining the respective string lengths of pearls or like elements to be employed in making up a necklace of the choker type, the measuring device is placed around the neck of the individual to be fitted with such form of necklace with the bead string A uppermost, whereupon said bead string A is adjusted to desired neck encircling position, and then the strand 12 of said bead string A is entered in the slot *a* of the measuring coupler element behind the bead 11 which terminates the adjusted neck encircling portion of said string A, so that the succeeding bead is lodged and held in the seating channel 17 (see Fig. 8). By noting the identifying member of the terminating bead, the number of pearls or the like, necessary to be strung to furnish a properly fitting top string of the necklace to be made, will be at once indicated. This operation is then repeated with respect to the bead strings B and C of the measuring device, the strands thereof being respectively engaged in the respective slots *b* and *c* of the measuring coupler element, whereupon the proper number of pearls or the like to be furnished for the respective strings thereof required to make up the necklace, so as to personally fit the individual measured, is easily and quickly determined. Not only this, but upon completion of such application of the measuring device to and upon the neck of the individual undergoing measurement, that individual may observe in a mirror (see Fig. 2) the effect and position or lie of the strings A, B and C, whereby to determine whether such lie is desired higher or lower, and generally as to what the appearance of the finished necklace will be when worn.

Since the neck size and neck muscular contours of different individuals may vary widely, it will be obvious that the use of the measuring device will readily and accurately predetermine the requirements as to bead or pearl string lengths for a necklace or the like to satisfactorily fit a given individual. Ordinarily in a plural string necklace, the top pearl string will require the minimum number of pearls or beads, the intermediate string or strings an increased number thereof, and the lowermost string the maximum number thereof. The numbers of beads or pearls required in the respective strings will vary considerably as to each other with respect to different individuals, not only by reason of varying neck sizes from small to large, but also by reason of variations in muscular structure or contours of the neck even in individuals having approximately the same neck size.

After measurement has been completed by the use of the measuring device of this invention, it is a simple matter to accordingly string pearls, beads or the like for production of a corresponding finished necklace. By use of the measuring device, it is therefore possible for either a manufacturer or a retailer to carry a stock of loose or

unstrung pearls, beads or the like, and, upon ascertaining the necessary information indicated by the measurement, thereafter immediately and accurately string said pearls, beads or the like, and then quickly assemble the strings to form the desired finished necklace or similar article with assurance of the satisfactory fitting thereof to suit the requirements of individual purchasers.

In Figs. 11 and 12 of the drawings there is shown a modified form of the measuring coupler element of the device, which, instead of the one-piece structure previously described, comprises a two-piece structure, the meeting ends of which are provided with cooperative separable clasp elements, so that the coupler elements not only simulates a clasp connection between meeting ends of a finished necklace or like article, but in so doing provides spacing allowance between the meeting ends of the measuring strings A, B and C substantially equivalent to that needed for a clasp connection with which the finished necklace or like article will necessarily have to be provided. Such modified construction of measuring coupler element comprises a body section 24 having the string anchoring eyes 14 along its rearward marginal portion and a female clasp element 25 at its forward marginal portion. Cooperative with said body section 24 is a separable companion body section 26, which is provided at its rearward marginal portion with a male clasp element 27 for cooperation with said female clasp element 25 of the body section 24, and at its forward end with the slotted coupler portion 16 for engagement by the measuring bead strings A, B and C. It will be obvious that in use and operation of the measuring device, the above described modified construction of coupler element will function, when its sections are joined together, in the same manner as already heretofore set forth relative to the first described embodiment of this invention.

Having now described our invention, we claim:

1. A measuring device for the purposes described comprising a desired number of beads of selected size, a flexible carrying strand upon which said beads are strung in successive abutting relation, a coupler means affixed to one end of the string of beads with which a selected bead of the free end portion of said string thereof may be engaged, whereby to form a circular measuring loop in said bead string, and at least a plurality of said beads which extend toward the free end of the string thereof having identifying numbers thereon corresponding to their numerical positions in the whole strung length of beads, counting from the end of the latter to which said coupler member means is affixed, whereby engagement with the coupler means of a selected numbered bead will denote the entire number of beads by which said measuring loop is formed.

2. A measuring device for the purposes described as defined in claim 1, including means at the free end of the string of beads operative to retain said beads in abutting relation.

3. A measuring device for the purposes described including a plurality of strings of beads, each string comprising a desired number of beads of selected size and a flexible carrying strand upon which said beads are strung in successive abutting relation, a coupler device having transversely spaced means at its inner end to which corresponding ends of said bead strings are respectively affixed to extend longitudinally therefrom in laterally spaced parallel relation, said

coupler device having at its outer end means with which said selected beads of the free end portions of said respective strings thereof may be respectively engaged, whereby to form respective circular measuring loops in said bead strings, and at least a plurality of said beads which extend toward the free end of each string thereof having identifying numbers thereon corresponding to their numerical positions in the whole strung length thereof, counting from the end of the string which is affixed to said coupler device, whereby engagement with the coupler device of selected numbered beads of the respective strings thereof will denote the entire number of beads by which each respective measuring loop is formed.

4. A measuring device for the purposes described as defined in claim 3, wherein each string of beads is provided at its free end with means operative to retain the beads thereof in abutting relation.

5. A measuring device for the purposes described as defined in claim 3, wherein the coupler device comprises separable parts one of which includes the bead engageable portion, and said parts having cooperative clasp means for releasably joining the same in connected relation.

6. A measuring device for the purposes described comprising a desired number of beads of selected size, a flexible carrying strand upon which said beads are strung in successive abutting relation, a coupler body to which one end of the string of beads is affixed for extension therefrom, a coupler portion at the outer end of said coupler body formed to provide a rearwardly open transverse seating cavity, the wall of said coupler portion having an indenting slot intersecting said seating cavity, whereby the bead supporting strand can be entered through said slot for seating a selected bead of said string thereof in said seating cavity to thereby form a circular measuring loop in said string of beads, and at least a plurality of said beads extending toward the free end of said string thereof having identifying numbers thereon corresponding to their numerical positions in the whole strung length of beads, counting from the end of the latter which is affixed to said coupler body, whereby engagement in the seating cavity of the coupler means of a selected numbered bead will denote the entire number of beads by which said measuring loop is formed.

7. A measuring device for the purposes described as defined in claim 6, including means at the free end of the string of beads operative to retain said beads in abutting relation.

8. A measuring device for the purposes described including a plurality of strings of beads, each string comprising a desired number of beads of selected size and a flexible carrying strand upon which said beads are strung in successive abutting relation, a coupler body having transversely spaced means at its inner end to which said strings are respectively affixed by ends thereof to extend longitudinally therefrom in laterally spaced parallel relation, said coupler body having a transverse coupler portion at the outer end thereof formed to provide a rearwardly open seating channel, the wall of said coupler portion having laterally spaced indenting slots intersecting said seating channel, whereby strands of said bead strings may be respectively entered through said respective slots for seating selected beads of said respective bead strings in said seating channel to thereby form a circular meas-

uring loop in each bead string, and at least a plurality of said beads which extend toward the free end of each bead string having identifying numbers thereon corresponding to their numerical positions in the whole strung length thereof, counting from the end of the latter which is affixed to said coupler body, whereby engagement in the seating channel of the coupler body of a selected numbered bead of the respective bead strings will denote the entire number of beads 10 by which each respective measuring loop is formed.

9. A measuring device for the purposes described as defined in claim 8, wherein each string of beads is provided at its free end with means operative to retain the beads thereof in abutting relation. 15

10. A measuring device for the purposes described as defined in claim 8, wherein the coupler body comprises separable parts one of which in- 20

cludes the coupler portion, and said parts having cooperative clasp means for releasably joining the same in connected relation.
